UNITED STATES PATENT OFFICE.

ALGER S. RIGGS, OF NEW YORK, N. Y., ASSIGNOR TO THERMIONIC CORPORATION, A CORPORATION OF DELAWARE.

AUTOMATIC SWITCH.

Application filed May 2, 1928. Serial No. 274,592.

The invention relates to automatic switches.

The prime object of the invention is to provide an improved automatic switch especially adapted for use in connection with 5 electrical phonographs.

Another object of the invention is to provide a device of the character described which will be adapted to automatically complete a circuit upon placing the stylus of a 10 phonographic pick up device upon a sound record and will automatically break the contact after the stylus has completed its course across the record.

One feature of the invention relates to the 15 provision of an arm mounted for rotation with the tone arm of a phonograph whereby movement of the tone arm will cause the arm to operate contact members.

A further feature of the invention relates 20 to the provision of a contact carrying arm mounted for a limited arc swing which will be adapted to close the circuit of an electric system upon actuation thereof by an actuating arm.

25 A further feature of the invention relates to the provision of means for maintaining the contacts together until they are released by the movement of the actuating arm.

Other objects and features will appear 30 from the following description in connection with the accompanying drawings in which

Fig. 1 is a top plan view of one embodiment of the present invention.

35 Fig. 2 is a bottom plan view of the invention illustrated in Fig. 1 with the switch closed.

Fig. 3 is a sectional view taken on line 3, 3 of Fig. 1 looking in the direction of the 40 arrow.

Like reference characters denote like parts in the several figures of the drawing.

In the following description and claims, parts, characteristic features and functions 45 will be identified by specific means for convenience of expression, but they are intended to be as generic in their application to similar parts or equivalent construction as the art will permit.

50 Referring to Fig. 1 of the drawings, for reproducing sounds a phonographic pickup device 10 is provided carried by a tone arm 11 mounted upon a swivel 12 which is rotatably secured through the top 14 of a phonograph cabinet. A stylus (not shown) car-

ried by the pickup device 10 is adapted to pass over a phonographic record 16 carried on the turntable 17. Vibrations of the stylus caused by the record may propagate sound waves from a diaphragm carried by the pickup device 10 or they may govern the transmission of electrical signals by the pickup mechanism 10 which may be carried upon a conductor through the tone arm 11 and the swivel 12 to a reproducing instrument in 60 connection with an electrical amplifying device. In either arrangement it may be desirable to employ an electrical circuit including conductors 18 and 19 for either operating the turntable of the phonographic device or 65 in conjunction with a reproducing and amplifying system.

For controlling the electrical circuit, a switch 20 is provided comprising a base 21 upon which is secured an insulating block 75 22 formed of bakelite, hard rubber or other insulating material provided with a pair of elongated apertures 23 and 24 through which threaded members 25 are adapted to pass for securing the insulating block in a relatively 80 adjustable position with respect to the base 21. A metallic contacting member 26 is provided secured to the block 22 by threaded connection therewith whereby a conductor connecting lug 27 may be permanently associated therewith for attachment with the conductor 18 of the circuit.

For completing the circuit a movable contact member 30 is provided mounted near one end of a resilient carrying member 31 of 90 conducting material, the opposite end of which is connected with the conductor 19 of the electrical circuit. The carrying member 31 is secured as at 32 to pivoted arm 33 for movement in and out of contact with the 95 contacting member 26. Rotation of the arm 33 is restricted by the provision of a pair of spring retaining members 34 secured to a fixed block 35 whereby movement of the arm 33 will cause a distortion of one or the other 100 of the retaining members tending to return the arm 33 to its normal position as indicated in Fig. 1 of the drawings. An angular bracket 37 is provided adjacent one end of the arm 33 for limiting the movement of the 105 carrying member 31.

For actuating the arm 33 to open or close the circuit a lever arm 40 is provided secured to and rotatable with the tone arm 11 but insulated therefrom by insulating bushing 41. 110

The opposite end of the lever arm 40 is provided with an angular upturned portion 42 adapted to form internal and external camming surfaces 43 and 44 respectively, which are adapted to coact with a pin 45 extending downwardly from the arm 33 to effect movement of the arm as will be hereinafter described.

For retaining the contact member 30 in position for completing the circuit, a catch member 50 is provided pivoted as at 51 adjacent the insulating block 22. The catch 50 is provided with a reduced portion 52 terminating in a shoulder 53 which is adapted to engage the outer end 54 of the arm 33 for securing the member 30 in contact with the member 26. A spring 55 is provided between the block 22 and the catch 50 for retaining the side of the catch 50 in contact with the end 54 of the arm 33. A pin 56 extends downwardly from the free end of the catch 50 which is adapted to be actuated by the camming face 44 for releasing the arm 33 from a contacting position.

In the operation of the device a pickup mechanism 10 is positioned over the outer portion of the phonograph record. In thus positioning the pickup mechanism, the actuating arm 40 is rotated causing the camming face 44 to act upon the pin 45 causing the arm 33 to swing until the contact member 30 carried thereby is in contact with the contact member 26 closing the electrical circuit which then energizes the pickup mechanism or completes the circuit for operating the turntable as shown in Figure 2 of the drawing. In this movement of the arm 33 its free end 54 is adapted to cam outwardly the catch member 50 until the end 54 of the arm 33 has passed the shoulder 53 at which time the spring 55 acts in reversing the direction of the catch mechanism whereby the edge 54 will be secured against the shoulder 53. As the pickup mechanism 10 proceeds across the face of the phonograph record towards its center the lever arm 40 is moved with it by engagement through the insulated bushing 41. When the end of the record is reached by the pickup mechanism 10 the camming face 44 of the lever arm 40 contacts with the pin 56 of the catch 50 camming it outwardly against the tension of the spring 55 thereby releasing the contact 54 from the shoulder 53, whereby it will resume its natural position, as shown in Fig. 1, through the action of the spring members 34.

Thus it may be seen the invention provides

a simple and efficient mechanism for completing an electrical circuit upon the positioning of a stylus upon a sound record and in like manner provides means for breaking the circuit when the stylus has reached the end of the record.

In accordance with the provisions of the patent statute, I have described my invention, but I desire it understood that it is not confined to the particular form shown and described, the same being merely illustrative, and that the invention can be carried out in other ways without departing from the spirit of my invention, and therefore, I claim broadly the right to employ all equivalent instrumentalities coming within the scope of the appended claims, and by means of which, objects of my invention are attained and new results accomplished as it is obvious that the particular embodiments herein shown and described are only some of many that can be employed to attain these objects and accomplish these results.

Having now described my invention, what I claim and desire to secure by Letters Patent, is:

1. In a phonograph the combination with a tone arm, of a switch, including an actuating arm movable with said tone arm, a contact carrying arm, a stationary contact, a cam surface on one extremity of said actuating arm, and a cooperating pin carried on said contact carrying arm whereby movement of the tone arm inwardly towards the outer periphery of a sound record groove cams said contact carrying arm towards said stationary contact.

2. In an automatic switch including a stationary contact, a movable contact, a pivoted arm for carrying said movable contact, a stationary block adjacent the pivoted end of said contact carrying arm, a pair of spring members on either side of said block adapted to engage either side of said pivoted arm for securing said arm normally in uncontacted position.

3. In an automatic switch including a pivoted contact carrying arm, a contact carried thereby, resilient means for carrying said contact and means for limiting movement of said contact with respect to said contact carrying arm.

Signed at New York, in the county of New York and State of New York, this 24th day of April, A. D. 1928.

ALGER S. RIGGS.
